UNITED STATES PATENT OFFICE.

JOHN J. CAREY AND PATRICK CAVANAUGH, OF LA SALLE, ILLINOIS.

BUTTER-JAR.

SPECIFICATION forming part of Letters Patent No. 269,005, dated December 12, 1882.

Application filed April 29, 1882. (No model.)

To all whom it may concern:

Be it known that we, JOHN JOSEPH CAREY and PATRICK CAVANAUGH, both of La Salle, in the county of La Salle and State of Illinois, 5 have invented a new and Improved Butter-Jar, of which the following is a full, clear, and exact description.

The object of our invention is to provide a new and improved vessel for packing butter 10 in such a manner that it will remain fresh and sweet, and will be protected from the action of the air.

The invention consists in a jar provided with an inner and outer cover, resting on packing-rings and held on the jar by means of clamps passed over a circular ridge on the outer cover, which clamps are provided in their lower hooks with rubber blocks, resting with their upper edges against the lower edge of an external collar of the jar, which collar is provided with beveled recesses. By moving these clamps out of the recesses and along the edge of the collar the outer cover will be held and pressed on the jar and its packing-rings.

Reference is to be had to the accompanying drawings, forming a part of this specification, in which similar letters of reference indicate corresponding parts in all the figures.

Figure 1 is a side elevation of our improved butter-jar, the lower parts being broken off. Fig. 2 is a longitudinal sectional elevation of the same on the line *x x*, Fig. 1. Fig. 3 is a detail perspective view of one of the clamps for holding the external cover on the jar.

The jar A, made of glass or earthenware, is provided at its top with an interior annular shoulder, *a*, upon which the inner cover or lid, B, is adapted to rest. Above this shoulder *a* the jar is provided with an interior shoulder, 35 *b*, of greater diameter, which is flush with the upper edge of the inner cover, B. A flat packing-ring, C, of rubber, leather, felt, or other suitable material, is placed on this shoulder *b* and on the edge of the lid B to cover the joint 40 of the lid and shoulder. A packing-ring, D, of rubber, leather, or felt, is placed on the upper edge of the jar A, and on this packing-ring D the exterior cover, E, of the jar is placed, this cover E being provided with an annular recess, 45 so that an annular ridge, *d*, which rests against the inner surface of the top of the jar, will be

formed on the under surface of the cover E. This cover E is provided on its upper surface with a circular ridge, F, along the edge. The jar is provided at its upper edge with an exterior collar, G, which is provided with beveled recesses H in its lower edge.

For the purpose of securing the cover E in place, we employ two clamps—one pivoted and the other rigid.

Two flat hooks, J' J'', are pivoted to each other to form the pivoted clamp J, and the rigid clamp is formed of a strip of metal, having its ends bent over in the shape of hooks to form a clamping-clip, K.

The butter having been placed into the jar A, the cover B is placed on the same. The packing-ring C is placed on this cover, and the packing-ring D on the upper edge of the jar, and then the cover E is placed on the jar. Strips 65 or blocks L of rubber are placed in the lower hooks or pockets of the clamps J and K to form an elastic bearing against the shoulder *b*. The upper hooks of the clamps J and K are passed over the ridge F, and the rubber 70 strip L of these clamps J and K rests against the edge of the recesses H at their deepest parts. By pushing the clamps J K partly around the cover E in the direction of the arrow *a'* the upper edges of the rubbers L of the 75 clamps J and K pass along the inclined edge of the recess, and from there along the lower edge of the collar G. The upper hook of the clamps J and K will thus be pressed on the ridge F, and will press the cover E on the upper edge of the jar, thereby closing this jar 80 absolutely air-tight, whereby the butter will be protected from the action of the air, and will remain fresh and sweet.

The cover can easily be removed if the clamps 90 J and K are pushed back in the reverse direction of the arrow *a'*.

Two clamps J or two clamps K may be used in place of one of each kind, as shown; but we prefer to use a pivoted and rigid clamp, 95 the former being more readily manipulated than the latter.

Having thus described our invention, we claim as new and desire to secure by Letters Patent—

1. The combination, with the jar A, of the inner cover, B, the exterior cover, E, and the

hook-ended clamps J and K, substantially as herein shown and described, and for the purpose set forth.

2. The combination, with the jar A, provided with the shoulders *a* and *b*, of the interior cover, B, the exterior cover, E, the clamps J K, and the packing-rings C D, substantially as herein shown and described, and for the purpose set forth.

3. The combination, with the jar A, provided with the shoulders *a* and *b*, and the external collar, G, having beveled recesses H, of the interior cover, B, the exterior cover, E, and the clamps J and K, substantially as herein shown and described, and for the purpose set forth.

4. The combination, with the jar A, provided with an exterior collar, G, provided with

beveled recesses H, of the interior cover, B, the exterior cover E, the clamps J and K, and the rubber strips or blocks L in the lower hooks of the clamps, substantially as herein shown and described, and for the purpose set forth.

5. The combination, with the jar A, provided with an exterior collar, G, having recesses H in its lower edge, of the covers B and E, the clamps J and K, the clamp J formed of two pivoted hooks, J' J'', and of the rubber blocks L, substantially as herein shown and described, and for the purpose set forth.

JOHN JOSEPH CAREY.
PATRICK CAVANAUGH.
